ELECTRIC METERING DEVICE

Leonard C. Truesdell, Kansas City, Mo.

Application July 9, 1943, Serial No. 493,981

3 Claims. (Cl. 194—1)

This invention relates to improvements in automatic coin operated metering devices of the electrical type, adapted to control the use of electric current for various purposes during limited time periods, and wherein the user may extend the metered service by depositing a coin in the device.

More particularly, the invention relates to the form and arrangement of coin receptacles adapted for interchangeable use in such devices, so that an enclosed coin receptacle may be bodily removed from the device for emptying and another similar receptacle be put in its place, wherein the electrical metering mechanism is automatically rendered inoperative whenever there is no coin receptacle properly applied in coin receiving relation to the device.

The principal object of the invention is to provide a simple and efficient coin collecting mechanism of the character indicated above, whereby coin collections from the metering device may be facilitated in an economical and orderly manner by the use of a plurality of interchangeable enclosed coin receptacles constructed in accordance with my invention. The coins are not handled or counted when the receptacle is removed from the device. Instead, the filled or partly filled receptacles may be taken to a central collection station for emptying and counting of the coins, while a duplicate empty receptacle is placed in the metering device to maintain the latter in proper operating condition.

The invention may best be understood by reference to the accompanying drawing, in which—

Figure 1 is a transverse sectional view of a metering device constructed in accordance with my invention;

Figure 2 is a bottom view of the device shown in Figure 1, with parts broken away to show certain structural details;

Figure 3 is a rear view of the device shown in Figure 1, with parts broken away to show details of construction of the coin control mechanism and the coin receptacle associated therewith; and

Figure 4 is a detail section of the coin receptacle removed from the metering device.

Referring to details of the embodiment of my invention illustrated in the drawing, 1 indicates a casing for housing the metering device, said housing consisting of a top wall 2, side walls 3, 3, and rear wall 4, together with a transparent partition 5 at the front of the casing for viewing a metering indicator 6 of the timing mechanism, indicated generally at 7. Said timing mechanism may be of any well known form, such as is

used commercially for providing electrical current to electrical appliances, such as lighting devices, electric refrigerators, or the like. The casing is also provided with a bottom wall 4a, which 5 may be detachable, as indicated.

In the form shown herein, the timing mechanism is electrically operated by a motor, indicated generally at 8, and is provided with a main service switch 9, which is adapted, as usual, to be cut off after a rotating element of the timing mechanism has been moved through a predetermined arc.

Details of construction of the timing mechanism need not be further described, as it forms no part of the present invention, excepting to point out the rotating shaft 10 forming part of the main rotating member thereof, which is adapted to be reset from time to time by means of a knob 11 at the rear of the casing 1. Resetting of the shaft 10 is controlled by a coin controlled time setting means of any suitable construction.

In the form shown herein, said coin controlling means consists of a rotating disk 15 fixed on the shaft 10 adjacent an upright partition 16 within the casing 1 and enclosed within a housing 17 at the rear of said partition. The disk 15 has a slot 18 formed in its periphery of such size as to receive a coin of predetermined size, such as 30 a quarter, when said coin is dropped through a slot 19 in the upper wall 2 and a registering slot 20 in the upper edge of the housing 17 which surrounds said disk.

Suitable locking means are provided for restraining rotation of the disk 15 excepting when a coin is deposited in the recess 18 of the latter. In the form shown herein said locking means comprises a flat spring 21 fixed to the rear face of the housing 17 and having a portion thereof 40 adapted to project yieldingly through a recess 22 in the housing 17. Said spring is arranged so that its lateral margins or stops 23, 23 are normally projected into the recess 18 of disk 15 when said recess is in coin receiving position, as indicated in Figure 3. Thus, when there is no coin in the recess 18, the stops 23, 23 at opposite sides of the spring 21 form abutments for engaging the proximate side walls of the slot 18 and lock the disk against rotation in either direction. The arrangement is such, however, that when a coin is inserted in the slot 18, the spring 21 will be elevated, so that the stops 23, 23 will no longer prevent rotation of the disk 15.

As a further precaution against rotation of the disk 15 unless a coin is inserted in its slot 18,

I provide a pair of auxiliary springs 24, 24 substantially smaller than the spring 21, but disposed at opposite sides of and spaced from the coin insertion slot 19, so that the ends of the springs 24 will be engaged with a wall of the slot 18 and prevent rotation of the disk 15 unless a coin is inserted in the slot 18.

Immediately below the disk 15 and the housing 17 which encloses the same, I provide means for supporting a detachable coin receptacle, indicated generally at 25. In the form shown herein, said receptacle consists of a cylindrical cartridge-like container, which is fully enclosed excepting for a slot 26 at its upper end and a removable closure member 27 at its lower end.

The receiving slot 26 for the receptacle is arranged to register with an opening 28 formed in the lower periphery of the housing 17 so as to permit a coin to drop by gravity out of the slot 18 when the disk 15 is rotated, so as to bring the slot 18 in registering position with the opening 28 at the bottom of the housing 17.

Means are provided for detachably mounting the receptacle 25 in the casing 1 in proper coin receiving relation to the coin controlled time setting means heretofore described. In the form shown herein, the cylindrical receptacle 25 is provided with a fin 30 extending longitudinally along one side thereof and adapted to have slideable engagement in a slot 31 formed in the rear wall 4 of the main casing 1. In addition, the partition member 16 is cut away, as indicated generally at 33, to accommodate the receptacle 25, and a pair of arcuate guide members 34, 34 is mounted along proximate margins of the receptacle 25 so as to provide a guide to permit endwise insertion of the receptacle from the bottom of the casing.

Any suitable means may be provided for holding the receptacle in its proper place in the casing. In the form shown, the bottom wall 4a is provided with a laterally sliding removable portion 35, as shown in Figures 1 and 3, arranged so that when the sliding portion 35 is removed rearwardly from the casing the receptacle 25 may then be bodily withdrawn by dropping it through the bottom of the casing.

Referring now more particularly to one of the principal features of my invention, it will be observed that I also provide a switch member 38, which is arranged to be engageable by the coin receptacle 25. Said switch may be of any suitable type to be normally open excepting when the coin receptacle 25 is inserted in its normal coin receiving position in the casing. In the form shown herein, the switch 38 consists of a device commercially referred to as a micro-switch and includes a spring pressed plunger 39, which is adapted to be engaged by the upper end of the receptacle 25 when the latter is moved upwardly into its normal coin receiving position, as shown in Figures 1 and 3. The arrangement is such that the spring pressed plunger 39 will be raised when engaged by the receptacle, so as to close the switch 38, but the switch will be automatically opened whenever the receptacle is removed from this position.

The switch 38 is placed in the current supply line which serves the timing mechanism and the main service switch 9, so that said timing mechanism will be rendered inoperative and current to service switch 9 will also be cut off, whenever the coin receptacle 25 is removed from its normal coin receiving position. In the form shown, the circuit connections just described consist of a

main line conductor 40 leading to the switch 9, and thence through conductor 41 to the timing motor 8, thence through conductor 42 to switch 38 to a second main line conductor 43. It will be understood, however, that the electrical connections may be varied so that the main line switch 9 may control a relay for a separate main line switch in a well known manner.

The operation of the mechanism above described is as follows: When it is desired to remove the receptacle 25 for emptying, the entire receptacle may be detached bodily from the casing by removing the sliding bottom partition 35 and then dropping the receptacle through the bottom wall of said casing. By thus removing the receptacle, the timing mechanism and the main supply switch will automatically be rendered inoperative until a receptacle is placed in coin receiving position. In practice, a plurality of duplicate coin receptacles is utilized, so that as soon as one receptacle is removed for emptying, another receptacle is inserted in its place.

One of the principal advantages in providing detachable coin receptacles in accordance with my invention is to make it possible to transport the filled or partly filled receptacles to a central station, where they may be emptied and the proceeds credited to the proper user.

The device is so arranged that the user himself may detach the receptacle and take it to the counting station, thereby eliminating the necessity of special collectors. Moreover, all handling and counting of the coins is done at the central station by trained operators, instead of at the time of removing the coin receptacle from each metering device, thereby affording a more satisfactory check on the proceeds of collections.

It will therefore be understood that for the broad purposes above stated, it is not necessary that the coin receptacles be completely sealed or locked, particularly when the user must transport the receptacle to the central counting station, since in such cases the user has custody of the receptacle until it is turned over directly to the receiving station.

In some cases, however, it may be desirable to provide the receptacles with a suitable lock, or at least with a simple sealing appliance, such as a strip of paper, or the like, which may also be used as a means of identification of the subscriber or user who turns in the receptacle.

In the form shown herein, a closure device for the receptacle 25 consists of the disk-like plug 27 threaded in the lower end of the receptacle 25 and provided with a plurality of unequally spaced recesses 45, 45 in its lower face. These recesses are adapted to be engaged by a suitable tool (not shown) having a series of prongs adapted to register with the recesses 45, 45, so as to facilitate the unscrewing of the closure member 27 from the receptacle.

It will, of course, be understood, however, that other and more complicated locking devices may be provided if desired.

It is to be understood that I do not wish to be limited to the exact embodiment of the device shown, which is merely by way of illustration and not limitation, as various other forms of the device will, of course, be apparent to those skilled in the art without departing from the spirit of the invention and scope of the claims.

I claim:

1. In combination with a coin operated metering device for electric currents, including a service current supply line, timing mechanism for

controlling said current supply line, coin controlled time setting means for said timing mechanism, an enclosed coin receptacle for receiving coins from said time setting means, and switch means in said current supply line cooperatively movable by said coin receptacle to close said current supply line when the latter is in coin receiving relation with said coin control means, and adapted to cut off the current supply when said coin receptacle is removed from its normal coin receiving position.

2. In combination with a coin operated metering device for electric currents, including a current supply line having a service switch, timing mechanism for controlling said switch, coin controlled time setting means for said timing mechanism, and an enclosed coin receptacle for receiving coins from said time setting means, and a second switch in said current supply line, said second switch having a control member normally in open position but engageable by said coin receptacle when the latter is in coin receiving relation with said coin control means to close said

second switch, whereby the current supply will be cut off when said coin receptacle is removed from its normal coin receiving position.

3. In combination with a coin operated metering device for electric currents, including a current supply line having a service switch, an electrically operated timing mechanism for controlling said switch having a motor driven from said current supply line, coin controlled time setting means for said timing mechanism, and an enclosed coin receptacle for receiving coins from said time setting means, and a second switch in said current supply line, said second switch having a control member normally in open position but engageable by said coin receptacle when the latter is in coin receiving relation with said coin control means to close said second switch, whereby the current supply will be cut off and said timing mechanism will be rendered inoperative when said coin receptacle is removed from its normal coin receiving position.

LEONARD C. TRUESDELL.
